UNITED STATES PATENT OFFICE.

WILLIAM L. HAWN, OF KANSAS CITY, MISSOURI, ASSIGNOR OF ONE-HALF TO ARCH KAVANAGH, OF KANSAS CITY, MISSOURI.

MATTRESS.

1,328,248.

Specification of Letters Patent. Patented Jan. 13, 1920.

Application filed October 2, 1919. Serial No. 328,017.

To all whom it may concern:

Be it known that I, WILLIAM L. HAWN, a citizen of the United States, residing at Kansas City, in the county of Jackson and State of Missouri, have invented certain new and useful Improvements in Mattresses; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to mattresses and particularly to a method of forming a welt edge around the top and bottom of the mattress to assist in maintaining the mattress in shape and to present a more symmetrical appearance to the finished product.

It is well known that mattresses have a tendency to break down at the edges and various attempts have been made to eliminate this tendency.

25 I have provided means whereby the mattress tick or covering may be sewed preliminary to introducing the filling, and tufting the same so that a substantially rectangular mattress will be formed with vertical edges which will not so easily break down as mattresses constructed under the known methods prior to my invention.

In carrying out my invention I prefer to fold the tick or covering back upon itself in laps spaced apart a sufficient distance so that when the edges of the laps are brought together, a cylindrical loop or welt may be formed by introducing filling material, sewing the meeting edges of the laps by a line of stitching and finally inverting the tick or covering so that the welts are on the outer edges, thereby forming a reinforcement around the entire upper edge as well as around the entire lower edge.

45 In the drawings,

Figure I is a perspective view of a portion of a mattress constructed in accordance with my invention.

Fig. II is a fragmentary sectional view through the tick or covering, showing the preliminary step of forming the open welt and the final step of closing it after the welt loop has been filled, and

55 Fig. III is an enlarged cross sectional view through a portion of the mattress, showing the welts in their final position.

Referring now to the drawings by numerals of reference:

1 designates a tick or flexible covering for the mattress, which may be formed into a bag or cover. The edges of the bag or cover are first folded back in the form of laps 2 and 3, which may be sewed together within the edges of the laps by lines of stitching 4 and 5, the laps being spaced apart so that when the edges 6 and 7 are brought together, they may be sewed in the form of a welt loop 8.

Preparatory to sewing the edges together, however, the loop 8 is filled with a suitable fibrous material 9 and then the edges are sewed together as at 10 to close the loop. For convenience in sewing, the loop is formed on the inside of the bag or covering and after the loop is closed by the lines of stitching 10, the bag is inverted or turned inside out, so that the welts are on the outside of the covering, as indicated in Figs. I and III. The mattress may then be filled with suitable fibrous material 11 and provided with the usual tufts 12.

The finished product will present a symmetrical appearance and the welts will have the appearance of heavy corded edges, which will not only assist in presenting stability to the finished product but will also maintain the mattress in a true rectangular form, reducing the liability of the edges breaking down when in service.

What I claim and desire to secure by Letters-Patent is:

1. The method of forming mattresses which consists in folding back the edges of a sheet of material to form laps spaced apart, stitching the laps together inside the edges thereof, introducing a filling material in the space between the laps, securing the edges of the laps together to form a welt, forming a bag, and introducing the filling material into the bag.

2. The method of forming mattresses which consists in folding back material to provide laps spaced apart, then introducing material in the space between the laps, sewing the edges of the laps together to form welts, connecting the edges of the material to provide a bag with the welts on the edges of the bag, and introducing a filling material into the bag.

In testimony whereof I affix my signature.

WILLIAM L. HAWN.
